United States Patent Office

Des. 225,772
Patented Jan. 2, 1973

225,772

COMBINED TRASH CONTAINER AND SUPPORT THEREFOR

Larry L. Stillinger, 2603 Washington St.,
Columbus, Ind.

Filed May 19, 1971, Ser. No. 145,095

Term of patent 14 years

Int. Cl. D7—05

U.S. Cl. D49—34

Fig. 1

Fig. 2

Fig. 3

FIG. 1 is a front elevation of a combined trash container and support therefor showing my new design;

FIG. 2 is a side elevation thereof; and

FIG. 3 is a rear elevation thereof.

I claim:

The ornamental design for a combined trash container and support therefor, as shown.
